Alvin L. Morris

Attorney

UNITED STATES PATENT OFFICE.

ROBERT MORSE WITHYCOMBE, OF SYDNEY, NEW SOUTH WALES, AUSTRALIA.

PROCESS OF MAKING RUBBER BRUSHES.

Original application filed March 31, 1925, Serial No. 19,708. Divided and this application filed February 2, 1926. Serial No. 85,572.

This invention, which is divided out of my application No. 19,708 filed March 31, 1925, for bath spray brush, patented May 31, 1927, No. 1,630,995, relates to a process of 5 making rubber brushes and proposes a novel method of treating a filamentous rubber strip stock in such a way as to produce brush heads for various purposes, characterized by the laminated arrangement of the strip 10 stock, producing a tufted congregation of the filaments at the working end of the brush head, and a solid base portion at the other end which may be suitably attached to any device or handle.

15 In its more specific adaptation, the process includes the step of tensioning the strip stock in the course of winding the brush, particularly when a "filler" is used in the center of the brush, so that certain layers of 20 the filamentous strip are drawn inward over the filler, thus concealing the latter and giving to the brush a general appearance of fullness which the amount of strip stock used would not otherwise justify, as well as 25 imparting to a brush so formed, advantages in function and use, some of which are referred to in the following specification.

In the drawings:—

Figure 1 is a side elevation of a brush constructed according to the process of the present invention.

Figure 2 is a section taken along the line 2—2 of Figure 1.

Figure 3 is a section taken along the line 35 3—3 of Figure 2.

The brush head 1 is formed of a strip of rubber, slotted transversely at close intervals along one longitudinal edge to form filaments, but uncut along the other longitudinal edge. The present process, in its broad application consists in applying a coating of some suitable vulcanizing fluid or cement to the unslotted portion of the strip or rubber, and then rolling said strip into a close convoluted body, the unslotted portion forming a solid base, having the vulcanizing coating between the several laminae, and a filamentous portion or tuft, constituting the working end of the brush. The process further contemplates the immersion of the brush head, thus formed, into boiling water or other suitable heating medium, to cause vulcanization of the base portion of the brush into an integral mass.

A brush formed in this manner requires 55 a considerable length of strip stock in the making, and is also quite heavy. Therefore in the interest of economy, lightness in weight, and other advantages it is sometimes desirable to use a central filler or plug about 60 which the rubber strip may be wound. In its specific adaptation to this form of brush, the process includes the additional step of tensioning the rubber strip as it is wound around the filler, the tension being preferably graduated from a maximum at the beginning of the winding operation to a minimum toward the end of such operation. Tensioning the strip in this manner has the effect of drawing the inner filamentous laminae inwardly over the filler as shown at 2 in Figure 3, and the progressive diminution of the tension causes the succeeding layers to be drawn in with progressively less acuteness, as shown at 3 and 4 in the drawing, the filler or plug being thereby concealed, and the brush being given an appearance of fullness, as though it were made in laminated form clear to the center.

In specific brushes, such as the one here 80 shown in which the filler takes the form of a perforated rose 5 adapted to be attached to a source of water flow 6, the inclined arrangement of the inner filaments, which is due to the tensioning of the strip while the 85 strip is being wound, produces novel advantageous effects which are more or less fully brought out in my above mentioned U. S. Patent No. 1,630,995, the paths of the jets of liquid emanating from the rose being 90 intersected by the inner layer or layers of filaments so that the jets are transformed into numerous films along the surfaces of the filaments, avoiding the direct impingement of the jets upon the surface to which 95 the brush is applied and consequent splashing, and at the same time constantly flushing the filamentous portion of the brush head; the liquid being supplied without waste to the contacting surfaces of said 100 filamentous portion and said surface, where the cleansing action is taking place.

It is to be understood that while my process is illustrated in its application to a specific form of brush, yet it is to be understood that it is applicable to the manufacture of any brush whatsoever in which a filamentous rubber strip is incorporated into

the brush by the process substantially as hereinbefore set forth.

Having described my invention what I claim as new and desire to secure by Letters Patent, is:—

1. The method of making brushes of that type which include a spirally wound rubber strip formed with filaments along one of its longitudinal sides, comprising winding the strip upon itself, while at the same time tensioning the non-filamentous side with a progressively varying tension.

2. The method of making brushes of that type which include a spirally wound rubber strip formed with filaments along one of its longitudinal sides, comprising winding the strip upon itself, while at the same time ten-

sioning the non-filamentous side with a progressively decreasing tension.

3. The method of making a brush of that type which includes a rose with a strip of rubber formed with filaments along one of its longitudinal sides, disposed about the periphery of said rose, comprising winding the strip spirally about said rose in a plurality of layers, while at the same time, tensioning the non-filamentous side of said strip with a progressively decreasing tension, whereby the layers will progressively overlie the rose, imparting fullness to the brush.

In testimony whereof I have hereunto set my hand.

ROBERT MORSE WITHYCOMBE.
